UNITED STATES PATENT OFFICE

124,190

DESIGN FOR FOUNTAIN LIP BRUSH

James L. Younghusband, Chicago, Ill.

Application February 21, 1940, Serial No. 90,410

Term of patent 7 years

To all whom it may concern:

Be it known that I, James L. Younghusband, a citizen of Dominion of Canada, residing at 30 West Hubbard Street, Chicago, Illinois, have invented a new, original, and ornamental Design for a Fountain Lip Brush, of which the following is a specification, reference being had to the accompanying drawing, forming a part thereof.

Fig. 1 is an elevational view of a fountain lip brush showing my new design, and Fig. 2 is a similar view with the cap removed.

I claim:

The ornamental design for a fountain lip brush, substantially as shown.

JAMES L. YOUNGHUSBAND.
